A. T. Robinson
INVENTOR

BY Victor J. Evans

ATTORNEY

WITNESS:

John H. Haug

UNITED STATES PATENT OFFICE.

ALFRED T. ROBINSON, OF SAGINAW, MICHIGAN.

COAL HOD.

Application filed September 12, 1923. Serial No. 662,313.

To all whom it may concern:

Be it known that I, ALFRED T. ROBINSON, a citizen of the United States, residing at Saginaw, in the county of Saginaw and State of Michigan, have invented new and useful Improvements in Coal Hods, of which the following is a specification.

The object of this invention is to simplify and improve the coal hod construction upon which I was granted U. S. Letters Patent, No. 935,409, on September 28, 1909.

Other objects and advantages will present themselves as the nature of the invention is understood.

15 In the drawing:—

Figure 1 is a perspective view of a coal hod in accordance with this invention.

Figure 2 is a sectional view approximately on the line 2—2 of Figure 1.

20 Figure 3 is a fragmentary sectional view on the line 3—3 of Figure 1.

Figure 4 is a perspective view of one of the handle sustaining ears.

The body of the coal hod is substantially 25 similar to that set forth in my referred to Patent No. 935,409, the same being pressed from a sheet of metal to include a flat bottom 1, sides 2, and a rounded rear end 3, and a pouring spout 4 formed on the outer 30 edge of the bottom 1.

In the manufacture of my referred to patent, I have found that the same cannot be cheaply manufactured and marketed because of the leg and brace construction 35 thereon. Also, I have found that the bail-like handle, being permitted to lie flat on the mouth of the body cannot be easily grasped and is for this reason objectionable.

In carrying out my present invention the 40 legs which support the open end of the hod at an upward inclination are constructed from a single strip of metal, and this metal strip is also designed to reinforce the bottom and sides of the hod. The side elements 45 of the strip, indicated by the numeral 5, are bolted to the sides 2 of the body. In a line with the bottom of the body the strips are given a half twist, as at 6 and have the ends which extend from the said twisted 50 portions bent upon themselves and continued in lapping relation with the said extensions. The last mentioned portions of the strips provide the legs for the body and the said legs are indicated by the numeral 7. 55 The inner elements of the legs are given a half twist, as at 8 to rest against the twists

6, and the connecting element for the strip, indicated by the numeral 9 is arranged flat against the bottom 1 and is riveted or otherwise secured thereto. The legs are disposed a considerable distance inward from the pouring spout 4.

The U-shaped bail-like handle 10 of the improvement has its ends bent upon itself to provide eyes 11, and these eyes are passed through round openings 12 in the ears 13. The ears are each formed from a single strip of metal, the body portions whereof being provided with openings and are bent downwardly upon themselves and continued to 70 provide base portions 14 that are riveted to the sides of the body. The outer corner of the body of each ear is bent at an inward angle as indicated by the numeral 15, and this angle portion is designed to be contacted by the bail to limit the swinging thereof in one direction and to hold the bail in a vertical position.

The upper edge of the body is beaded outwardly and the arms of the bail are inclined 80 toward each other so that the said arms will contact with the beads 15 to limit the swinging of the bail in an opposite direction. In this manner it will be seen that the bail is sustained at an upward angle with respect 85 to the body in either of its positions so that the said bail may be readily grasped by the operator.

Having described the invention, I claim:—

1. A coal hod comprising a substantially 90 rectangular body, legs therefor for sustaining the bottom of the body at an inclination, said legs being constructed from a single strip of metal including side members which are secured to the sides of the body, said sides directly below the body being of a half twist and from thence extended and bent upon themselves and continued in a line with the first mentioned extensions and thence given a half twist 95 to rest against the first mentioned twist, and the connecting element for the legs underlying the bottom of the body and secured thereto, and a bail handle pivotally connected to the sides of the body and sustained at an upward angle with respect 100 to the body in any of its positions.

2. A coal hod comprising a substantially 110 rectangular body, legs therefor for sustaining the bottom of the body at an inclination, said legs being constructed from a single strip of metal including side mem-

bers which are secured to the sides of the body, said sides directly below the body being of a half twist and from thence extended and bent upon themselves and continued in a line with the first mentioned extensions and thence given a half twist to rest against the first mentioned twist, and the connecting element for the legs underlying the bottom of the body and secured thereto, angle ears secured to the sides of the body and having openings therein and their outer corners bent in the direction of

the body, and a bail having its ends bent to provide eyes which are passed through the openings in the ears, and the sides of the said bail being in the path of contact with the edge of the body when swung to one position and designed to be contacted by the inturned corners of the ears when swung to a second position whereby the bail is at all times sustained at an upward angle with respect to the body.

In testimony whereof I affix my signature.

ALFRED T. ROBINSON.
